UNITED STATES PATENT OFFICE.

FORÉE BAIN, OF CHICAGO, ILLINOIS, ASSIGNOR OF ONE-HALF TO CHARLES B. ASKEW, OF SAME PLACE.

REGULATOR OR RHEOSTAT.

SPECIFICATION forming part of Letters Patent No. 427,032, dated May 6, 1890.

Application filed January 21, 1890. Serial No. 337,575. (No model.)

To all whom it may concern:

Be it known that I, FORÉE BAIN, a citizen of the United States, residing at Chicago, Cook county, State of Illinois, have invented certain new and useful Improvements in Regulators or Rheostats, of which the following is a specification.

My invention relates to a regulator or rheostat; and it has for its object to provide a rheostat which shall be simple and compact and at the same time capable of carrying a heavy current without danger; and to these ends my invention consists in a regulator or rheostat constructed substantially as herein-after set forth.

In the accompanying drawing I have shown a longitudinal section of a rheostat embodying my invention.

In the use of electric currents, especially where it is desired or necessary to use comparatively high-tension currents, it is often necessary to use a regulator or rheostat in order to control and regulate the current in the translating devices, which may be lamps, motors, or other well-known devices. Especially is it desirable to use such rheostats in the lighting of theaters, for instance, or in the working of mines or other places where space is an element and it is necessary to economize in this regard; and one of the special objects of my invention is to provide a rheostat which can be used under such circumstances, and which will occupy little space and still be capable of carrying a heavy current without danger of destruction of the rheostat or of creating a fire and destroying the surrounding material. Many devices have been made having this general idea; but I have found from actual experiment that the device I am about to describe is thoroughly practical and efficient for the purposes desired.

In carrying out my invention I make use of some conductor preferably having a high resistance to the passage of electric currents to form the coils or sections of the rheostat, and I immerse these coils in some liquid which shall have the capacity of carrying off the heat due to the passage of the current through the resisting medium and at the same time that will not materially reduce the electrical resistance.

In the drawing, A represents a box made of any suitable material, (shown as having an extended top B,) upon which are mounted the terminals of the electric circuit C C', one of which is connected to an ordinary switch D and the other to a contact-plate E. The switch is adapted to move over and rest in contact with any one or more of a series of contact-pieces E' E², &c., to which the terminals of the resisting medium F are connected. This resisting medium may be of any usual material—such as fine metal wire, carbon, or the like—and may be arranged in any desired form, so as to carry the resistance of the electric current flowing through the circuit C C' and through one or more of the coils or sections of the resisting medium. In the present instance I have shown this medium as composed of a number of coils of metal mounted in a frame G, which is adapted to fit into the box or case A, and there may be one or more of said frames, according to the necessities of the case. When in use this box contains a liquid H, which preferably completely submerges the coils or sections of the resisting medium, and this liquid may consist of water, oil, or other fluid, the essential requisite being that it shall be a non-inflammable fluid and capable of carrying off or absorbing the heat generated in the resistance medium.

I have found from actual use that a resistance medium of, say, No. 20 iron wire submerged in a vat containing water is capable of carrying for an unlimited time a current of one hundred and fifteen ampères, and while, of course, the water decreases the resistance of the coils I have found that this decrease is very small, being practically not over two per cent., while the carrying capacity of the resistance medium is increased many times, as it is well known that a wire of this character exposed to the air will melt under the influence of a current of a very small number of ampères. The water or other liquid carries off or absorbs the heat that is generated by the passage of the current and prevents the fusion of the wire and its consequent destruction. Moreover, in case the resistance should become overheated the fluid prevents the liability of setting fire to the surrounding materials. In

this way I am enabled to provide a regulator or rheostat which is extremely compact and safe and capable of use in many places where the ordinary resistance devices could not be 5 conveniently used, and, as before stated, the carrying capacity of the resistance medium is increased in a very large proportion by the addition of the fluid, while its resistance qualities are reduced in a very small percentage. 10 Moreover, the resistance medium is uniform and practically stationary, as it cannot increase in temperature beyond the boiling-point of the liquid in which it is submerged.

Having thus described my invention, what 15 I claim, and desire to secure by Letters Patent, is—

1. A regulator or rheostat consisting of an electric conductor offering a high resistance to the passage of the electric current im-

mersed in a heat-conducting liquid which is 20 practically a non-electric conductor, substantially as described.

2. A regulator or rheostat consisting of a vessel containing a heat-conducting liquid which is practically a non-electric conductor, 25 an electric conductor which offers a high resistance to the passage of the electric current immersed in said liquid, and electric connections for said electric conductor mounted on the case, substantially as described. 30

In testimony whereof I have signed my name to this specification in the presence of two subscribing witnesses.

FORÉE BAIN.
